1 Sheet Drawing. 6 Pages Specification

A dual purpose article of manufacture is provided in the form of a hollow, cylindrical core member which may first be used as a support for winding sheet material or the like, and subsequently as a hair curler. The core member is preferably made of polymeric material, and desirably is provided with a roughened surface. The walls of the core member may also be perforated, and may be provided with radial projections to aid in curling human hair.
